UNITED STATES PATENT OFFICE.

HAZLEHURST R. NOYES, OF SAVANNAH, GEORGIA.

ROTARY GAS-ENGINE.

1,016,764.

Specification of Letters Patent.

Patented Feb. 6, 1912.

Application filed February 13, 1909. Serial No. 477,617.

To all whom it may concern:

Be it known that I, HAZLEHURST R. NOYES, a citizen of the United States, and resident of Savannah, county of Chatham, 5 State of Georgia, have invented certain Improvements in Rotary Gas-Engines, of which the following is a specification.

My invention relates to gas engines, and more particularly to rotary gas engines of 10 the two-cycle type, wherein gas generated from gasolene in a vaporizer, or other gas, may be economically and efficiently used as a motive agent.

My object is to provide a rotary gas engine of the two-cycle type, having a minimum number of parts compactly and simply arranged, and adapted to furnish motive power at a minimum cost.

With this object in view, my invention 20 consists in the novel construction and combination of parts, as hereinafter described with reference to the accompanying drawings, and more particularly pointed out in the claims.

25 In the drawings: Figure 1 is a central transverse section of an engine embodying my invention; Fig. 2 is a longitudinal section thereof; Fig. 3 is an end elevation; Fig. 4 is an end elevation of the rotary carrier or abutment; and Figs. 5 and 6 are details of the sliding pistons.

Referring to the drawings, in which the same reference characters relate to the same or corresponding parts in all the views, 35 mounted within a casing E is a rotary carrier or abutment F secured to a driving shaft G journaled in suitable bearings in the heads E' closing the ends of the casing E. Extending from the opposite sides of 40 the casing E are suitable lugs or ears H, through which pass bolts I into a suitable bed-plate or foundation I' forming the support for the engine.

The rotary carrier F is of circular cross 45 section, and preferably cored or recessed, as shown at P, on opposite sides, to lighten the same, and is provided with suitable packing on the opposite ends bearing against the heads E' of the cylinder, as usual in this 50 type of engines.

The interior of the casing E is a mixed 55 contour of a circular arc and an ellipse, the upper portion for slightly more than ninety degrees, or approximately a quadrant, constituting the circular arc, and the remainder

following the contour of an ellipse. This rotary carrier or abutment F is in close contact throughout the circular arc at the top, and in tangential contact only at the bottom, thus dividing the casing into two chambers 60 Q and Q' on opposite sides of the carrier or abutment, of substantially crescent shape, as shown clearly in Fig. 1, one of these chambers serving as a compression chamber and the other as an explosion chamber. 65 Slidably mounted in suitable recesses at equidistant points around the circumference of the rotary carrier are three pistons L', L², L³, each of which is composed of two sections dove-tailed together, as shown in 70 Figs. 5 and 6, two springs N being seated in recesses in the opposite sections in alignment, as shown in Fig. 6, tending to press the sections apart, thereby maintaining the 75 edges in contact with the cylinder heads.

In order to press the piston outward when the engine is at rest and at the beginning or commencement of the rotary movement, I provide two helical springs M seated in recesses O in the piston wings, and having 80 their inner ends bearing upon the bottoms of the recesses in the rotary carrier. After the engine is in operation, the function of these springs is affected by the centrifugal force, which tends to throw the piston wings 85 outwardly against the interior surface of the chamber. The walls of the casing or cylinder E are hollow, providing a space K for the introduction of a cooling medium, such as water, as ordinarily used in this type 90 of machines.

The letter A' indicates an inlet pipe which is adapted to receive its supply from a vaporizer and mixer, not shown, and conduct the mixed air and gas through an inlet 95 opening A'' into the compression chamber Q of the engine, the latter being connected through a port B'' and pipe B' to the transmission valve chamber T', containing the transmission valve T which controls the 100 transmission of gas mixture from the said compression chamber Q to the explosion chamber Q' by way of the pipe C' and port C''. The pipe C' is provided with an ordinary check valve V to prevent the back-flow 105 of gas from said explosion chamber. Located at a suitable distance from the admission port C'' of the explosion chamber is a suitable spark plug S which is adapted to spark and fire the explosive mixture as 110

the piston wings L' , L^2 , L^3 successively pass the same, the sparking device shown for illustration simply being of the jump-spark type. At the opposite end of the explosion chamber to the inlet admission port C'' , is the exhaust D , through which the spent gases pass into the atmosphere or elsewhere.

5 The piston wings L' , L^2 , L^3 are so disposed that, as each wing passes the gas inlet port A'' , it closes the chamber Q to further admission of gas and begins to compress the gas contained therein, continuing such compression until the piston in advance or the active pressure piston has passed the 10 compressed gas admission port C'' and approaches the sparking device, the parts being so proportioned that this point will be reached when the active compressing piston has traveled about three-quarters the distance between the gas admission port A'' and the compressed gas outlet port B'' . At this time the valve gear operates to open the valve T to permit the compressed gas to 15 pass into the explosion chamber.

20 Referring to Fig. 3, it will be observed that this valve gear comprises essentially a three-point cam R mounted upon the shaft co-operating with an oscillating rod U pivotally supported on the cylinder head E' and 25 normally pressed into contact with the cam by a spring W , which rod is connected by suitable means, such as a link u , with a sleeve X slidably mounted on the cylinder head E' carrying, at its upper end, a pivoted 30 trip x adapted to be operated by a stop y fixed to the cylinder head. This trip is so arranged, it will be observed, as to engage a sleeve y' carried by the valve rod Y , a spring x' interposed between the sleeve y' and the 35 lower end of the valve chamber T' operating to quickly seat the valve T when the cam has 40 passed the admission point, and the trip x released from the sleeve y' .

45 It will be observed from the foregoing description that the arrangement is such as to provide a simple and efficient compression of the gas by one sliding piston, the transfer of such compressed gas into an independent explosion chamber where the successive 50 volumes of compressed gas are ignited and exploded in rapid succession as the series of pistons pass, first, the gas admission port of the gas compression chamber, second, the compressed gas admission port for the explosion chamber, and, third, the spark plug. The impetus given to each piston as the explosion occurs is sufficient to impart rapid 55 rotative movement to the rotary carrier, and thereby to the drive shaft.

60 I claim as my invention:

1. In a rotary gas engine, the combination of a rotary carrier, a casing in which said carrier is mounted so as to rotate and with whose inner face the carrier contacts 65 at opposite points so as to divide the inte-

rior of the casing into two chambers, one on each side of the carrier, an inlet and outlet for each chamber whereby one chamber will constitute a compression chamber and the other a combined explosion and exhaust 70 chamber, a series of pistons slidably mounted within the carrier and contacting at all times with the inner surface of the casing, a valved connection outside of the chambers between the delivery of the compression chamber and the inlet of the explosion chamber, means whereby the rotating carrier is caused to operate said valve at intervals, and means for exploding the compressed mixture in the explosion chamber 75 whereby it will drive forward the piston in advance of it and will cause said piston to drive from the exhaust the spent gases ahead of it.

2. In a rotary gas engine, the combination 80 of a casing with an internal contour comprising an elliptical section and approximately a quadrant of a circular section, a rotary carrier mounted in the casing with its periphery in close contact with the circular section and in tangential contact at the opposite side of the casing whereby said carrier divides the casing into two chambers, one on each side thereof, one chamber serving 85 as a compression chamber and the other as an explosion chamber, a plurality of sliding pistons mounted in said carrier and in constant contact with the inner face of the casing, an inlet and outlet communicating 90 with each chamber within the casing, a valved passage connecting the outlet of the compression chamber to the inlet of the explosion chamber, means whereby the carrier is caused to operate the valve in said passage 95 at intervals, and means for exploding the mixture in the explosion chamber.

3. In a rotary gas engine, the combination 100 with a casing of a drive shaft, a rotary carrier mounted upon said drive shaft and dividing the casing into two chambers on opposite sides of the carrier, pistons slidably mounted in said carrier, a conduit connecting the two chambers, a casing having a valve therein interposed in said conduit 105 between the chambers, a valve rod by which said valve is carried, a cam on the drive shaft for operating the valve, connections between the valve rod and the cam whereby the valve is operated and caused periodically to permit the flow of compressed gas from one chamber to the other, and means for exploding the compressed gas in the latter chamber, substantially as described.

4. In a rotary gas engine, the combination 110 of a casing, a drive shaft, a rotary carrier mounted upon said shaft and dividing the casing into two chambers on opposite sides of the carrier, pistons slidably mounted in said carrier, a conduit connecting the two chambers, a valve interposed in said conduit 115

120

135

between the chambers, a valve rod, means acting thereon to close the valve, a cam on the drive shaft, a slide operated by said cam, a trip on said slide for engaging the valve rod, and a stop for engaging said trip and releasing it from engagement with the valve rod when the valve has reached the limit of its opening movement, thereby permitting flow of compressed gas from one chamber 5 to the other of the casing, and means for

exploding the compressed gas in the latter chamber, substantially as described.

In testimony whereof, I have signed my name to this specification, in the presence of two subscribing witnesses.

HAZLEHURST R. NOYES.
